WINDING DRUM FOR HAND BRAKES

Raymond C. O'Connor, Chicago, Ill., assignor to
 Union Railway Equipment Company, Chicago,
 Ill., a corporation of South Dakota

Application November 7, 1932, Serial No. 641,547

5 Claims. (Cl. 254—149)

Mechanism of the class to which the present invention belongs includes a hand wheel and pinion in mesh with the teeth of a gear wheel, which in turn carries the winding drum to which 5 the brake chain is attached.

The object of the present invention is to provide a winding drum which is separable from the gear wheel with which it is associated, but which may be readily and easily mounted on the hub 10 of the gear wheel or removed therefrom as occasion may require. By thus making the winding drum separable from the gear wheel, it is possible to utilize gear wheels of standard size with winding drums of varying size or configuration 15 to accommodate variations in the size of the chain links or in the power ratio applied to the brake chain.

Furthermore, the arrangement is one which readily permits removal and substitution of the 20 parts in case of breakage, and permits the drum to be made of harder metal than the gear, if so desired, to resist wear or breakage.

Further objects and details of the invention 25 will appear from the description thereof, in conjunction with the accompanying drawings, wherein,—

Figure 1 is a vertical sectional elevation of the gear assembly including the winding drum of the present invention;

30 Fig. 2 is a face view of the gear and drum on a somewhat smaller scale, taken on line 2—2 of Fig. 1;

Fig. 3 is a face view of the drum;

35 Fig. 4 is a face view of the gear and drum showing a slightly modified form of construction;

Fig. 5 is a vertical sectional elevation taken on line 5—5 of Fig. 4;

40 Fig. 6 is a sectional view taken on line 6—6 of Fig. 5; and

Fig. 7 is a sectional view taken on line 7—7 of Fig. 5.

Referring first to the construction shown in Figures 1, 2 and 3, the separable winding drum 10 of the present invention is associated with a spur gear 11, the teeth of which mesh with a pinion 12 formed on a shaft 13, the outer end 14 of which is tapered to receive the hub 15 of a hand wheel 16.

50 The gear 11 is mounted upon a stub shaft 17, the ends of which are carried by the outer and inner walls 18 and 19 respectively of a housing which encloses the operating mechanism. The gear 11 comprises a flat web or body 20, a toothed 55 rim 21, and a hub 22, which hub is inwardly ex-

tended to afford a mounting for the winding drum which will presently be described.

The hub 22, at its inner and outer ends, is journaled upon bushings 23, each of which is provided with a flange 24 which overlaps the 60 proximate end of the gear hub, the bushings being held in position by contact of the outer and inner housing walls 18 and 19.

The winding drum in the form now being described comprises a base plate 25 of irregular 65 contour, but in general of pentagonal configuration, and provided with four rivet holes 26 adapted to receive rivets or bolts 27 extending through registering apertures in the web of the gear wheel. Obviously, where greater facility in removal is desired, bolts rather than the rivets shown can be employed.

The base plate 25 is offset to afford an inner winding drum section 28 which coacts with an outer winding drum section 29 in spaced relation thereto, to afford an intervening groove or channel 30 of sufficient depth to receive the alternate chain links 31 which stand in edgewise relation to the drum and which are connected by the intervening chain links 32 which lie flatwise upon the surfaces of the inner and outer drum sections 28 and 29.

75 The inner and outer drum sections are connected by a series of spokes or web sections 33, the drum as a whole, including the base plate 85 25, being integrally formed as a single casting. The inner drum section 28 is provided with an inwardly extending flange 34 which stands in opposed relation to a similar inwardly extending flange 35 constituting part of the outer drum 90 section, the two flanges affording the channel walls for the reception of the alternate chain links.

95 The flange 35 has formed around its inner edge a circular marginal flange 36 which bears directly upon the outer end of the gear hub and serves to support and reinforce the winding drum at this point, but it will be noted that the flange 34, together with the spokes or webs 33, terminate slightly outside of the surface of the hub to afford a clearance around the hub at all points save the region of contact afforded by the outer drum sections.

100 As shown in Fig. 3, the inner and outer drum sections are of substantially polygonal formation to afford flat winding surfaces 37 upon which the intermediate chain links lie flatwise, with the alternate chain links standing edgewise and within the groove or channel at the angles afforded by the intersection of the flat winding 110

surfaces. The inner and outer sections of the winding drum on one side are extended to afford an anchorage 38 provided with an aperture 39 adapted to receive a headed anchor pin 40 or 5 rivet which is entered through the terminal link of the chain, and in order to afford access to the inner end of the anchor pin, the gear 20 is provided with a registering aperture 41.

In assembling the parts just described, the 10 winding drum will be slipped into place with its rivet or bolt holes in registering relation with those formed in the gear wheel, after which rivets or bolts are inserted, which in conjunction with the contact afforded at the outer end of 15 the hub, serve to maintain the parts in rigid relation to one another.

The construction shown in Figs. 4 to 7 inclusive is similar to that previously described, in 20 all respects save the method of mounting and holding the winding drum in position upon the hub of the gear. In this instance the gear 20 is provided with a hub 42 which is squared at its inner end 43, the outer end 44 of the hub, however, being round, as indicated in Fig. 7.

25 The winding drum is formed with a body portion 45, the inner portion 46 of which is squared to closely embrace the squared portion 43 of the hub, while the outer portion 47 is circular to closely embrace the circular portion 44 of the hub.

30 The winding drum comprises an inner winding portion 48, an outer winding portion 49, and connecting ribs or spokes 50, but the winding surface and its relation to the chain are in all 35 respects similar to that previously described, so that further description thereof is deemed unnecessary.

35 The winding drum is held in position upon the hub by the provision of a washer 51, which is interposed between the bushing flange 24 and the 40 end of the hub, the washer being of sufficient width to overlap the end of the winding drum so as to prevent displacement thereof.

45 The bushings 23 stand in close contact with the proximate walls of the housing, so that when the parts are thus assembled, longitudinal displacement of the winding drum will be prevented.

50 The manner of mounting the drum is obvious from the above description, but in this instance it is not necessary to provide any form of positive connection with the web of the gear, since the square formation of the hub and drum prevents relative rotative movement between the parts. This form of construction is particularly desirable in cases where it is advantageous to provide 55 for a quick removal or replacement of the winding drum as occasion may require.

60 Although in the forms shown, the drum is of pentagonal formation having flat sides which afford desirable contact faces for the chain links, it is not the intention to thus limit the invention, since other configurations of the winding surfaces are contemplated, and in like manner the particular methods of mounting the separable winding drum may be changed or modified within 65 the scope of the appended claims without departing from the spirit of the invention.

I claim:

70 1. In a device of the class described, the combination of a gear wheel and mounting for the same, a hub extending from the gear wheel, a winding drum separable from the gear wheel and removably mounted upon the hub, and comprising

ing inner and outer sections standing in spaced relation to one another to afford a channel and to afford inner and outer winding surfaces contiguous to the channel, and a brake chain having its alternate links standing edgewise and within the channel and having intervening links lying flatwise upon the inner and outer winding surfaces, and spaced connecting web members between the inner and outer drum sections and located at points between the edge standing links. 80

2. In a device of the class described, the combination of a gear wheel and mounting for the same, a hub extending from the gear wheel, a winding drum separable from the gear wheel and removably mounted upon the hub, and comprising inner and outer sections affording flat peripheral faces and spaced to afford an intervening channel, spaced web members connecting the inner and outer sections, the outer section contacting the hub and the inner section being held in non-rotative relation, and a chain anchored to the drum and having its alternate links standing edgewise within the channel and the intervening links lying flatwise upon the winding surfaces contiguous to the channel. 85

3. In a device of the class described, the combination of a gear wheel and mounting for the same, a hub extending from the gear wheel, a winding drum separable from the gear wheel and removably mounted upon the hub, and comprising inner and outer sections affording flat peripheral faces and spaced to afford an intervening channel, spaced web members connecting the inner and outer sections, the outer section contacting the hub and the inner section being rigidly secured to the gear wheel, and a chain anchored to the drum and having its alternate links standing edgewise within the channel and the intervening links lying flatwise upon the winding surfaces contiguous to the channel. 90

4. In a device of the class described, the combination of a gear wheel and mounting for the same, a hub extending from the gear wheel, a winding drum separable from the gear wheel and removably mounted upon the hub, and comprising inner and outer sections affording flat peripheral faces and spaced to afford an intervening channel, spaced web members connecting the inner and outer sections, the outer section contacting the hub and the inner section being provided with a base flange lying in flatwise contact with the web of the gear wheel and being rigidly secured thereto, and a chain anchored to the drum and having its alternate links standing edgewise within the channel and the intervening links lying flatwise upon the winding surfaces contiguous to the channel. 100

5. In a device of the class described, the combination of a gear wheel provided with an outwardly extending hub squared upon its inner portion and circular upon its outer portion, a winding drum comprising inner and outer winding sections standing in spaced relation to afford an intervening channel, and a body portion squared in part on its interior to fit upon the squared portion of the hub and circular in part upon its interior to fit upon the circular portion of the hub, and a chain having its alternate links standing edgewise within the channel between the drum sections and having the intervening links lying flatwise upon the winding inner and outer drum surfaces. 105

RAYMOND C. O'CONNOR.
